UNITED STATES PATENT OFFICE.

HARRY A. HOUSEMAN, OF PHILADELPHIA, PENNSYLVANIA, ASSIGNOR TO
STANDARD MACHINE COMPANY, A CORPORATION OF PENNSYLVANIA.

CIRCULAR-KNITTING MACHINE.

SPECIFICATION forming part of Letters Patent No. 694,382, dated March 4, 1902.

Application filed April 18, 1901. Serial No. 56,348. (No model.)

To all whom it may concern:

Be it known that I, HARRY A. HOUSEMAN, a citizen of the United States, residing at Philadelphia, county of Philadelphia, and State of Pennsylvania, have invented a new and useful Improvement in Circular-Knitting Machines, of which the following is a full, clear, and exact description, reference being had to the accompanying drawings, which form a part of this specification.

My invention has for its object the production of a stocking which at the apex of the heel and toe portions shall have a different-colored thread from that of the remainder of the heel and toe.

My invention consists, speaking broadly, in providing mechanism which shall during the reciprocation of the machine in forming the heel or toe automatically change the thread-carrier, so that at the apex of the heel or toe a different-colored thread from that of the remainder of the heel or toe may be introduced.

I will first describe the embodiment of my invention as illustrated in the accompanying drawings and then specifically point out the invention in the claims.

Figure 1 is a plan view of a knitting-machine cylinder with my improved device attached. Fig. 2 is a side view of the same. Fig. 3 is a front view of the same. Fig. 4 is a detail rear view of the cam-plate and connections for raising the thread-carrier cams. Fig. 5 is a detail section on the line 5 5 of Fig. 4. Fig. 6 is a side elevation of the thread-carriers. Figs. 7, 8, and 9 are diagrams showing the operation of the thread-carriers. Fig. 10 is a section on the line 10 10 of Fig. 3. Fig. 11 is a plan view of the rack-plates with all the needles in action. Fig. 12 is a perspective view of a portion of the rack-plate with the pivoted raising-cam attached. Fig. 13 is a diagram of a portion of a stocking, showing a partially-colored heel and toe.

The machine in which I have embodied this invention is that patented to me April 30, 1895, No. 538,518.

In this specification and in the accompanying drawings I will neither describe nor illustrate the details of construction of the ma-

chine, but will merely illustrate and describe such parts thereof as are necessary to an understanding of this invention.

A is a portion of the main frame of the machine; B, the cam-cylinder support; C, the cam-cylinder; D, the needle-cylinder.

E' are the rack-plates, which in accordance with my patent before mentioned are in operation during the formation of the heel and toe for the purpose of automatically throwing out and in certain needles for the purpose of producing the heel or toe of a stocking. These rack-plates are respectively operated by the pawls e e', as in my previous patent. The pawls e e' are pivoted to the arms e² e³, respectively, which arms are attached to the ring e⁴. As in my previous patent, the ring e⁴ has the projecting arms e⁵, having rollers e⁶, operated by the cams F, which cams are given a reciprocating motion at the proper time by the gear X and rack x', which rack and gear also reciprocate the cam-cylinder during the formation of the heel and toe, as fully disclosed in my previous patent before mentioned. Connected to this ring e⁴ is an arm G. This arm G during the reciprocating work of the machine by the ring e⁴ is given a constantly-reciprocating movement.

H is a cam-plate pivoted to the frame h, secured to the frame of the machine. Within this cam-plate H and vertically movable therein is the slide h', having at opposite sides and different elevations projections h² h³. The lever G in its reciprocation will strike either projection h² or projection h³, dependent upon the position of the slide h', and thus move the cam-plate H in one direction or the other. On the side of the cam-plate H is the high cam-surface H' and low cam-surface H². Upon these cam-surfaces rests the end of the vertically-movable plunger I. The lower end of this plunger I is beveled, as at i. When the cam-plate H is moved in one direction through the action of the arm G upon the projection h², the plunger is carried from the low portion H² to the high portion H', and when the cam-plate moves in the opposite direction the plunger will by gravity descend to the low portion or surface H². It will thus be seen that, dependent upon the position of

the cam-plate H, the plunger I is elevated or depressed. Connected to the plunger I is a block I', carrying the cams I² I³. Each cam is in action essentially a pair of cams, in that 5 different portions act on different objects. Cam I³ is at a higher level than cam I². The face of each cam has a cut-away portion i² i³, respectively. The portion i² of the cam I² is at the opposite end of the length and height 10 from that of the portion i³ of the cam I³. J J' are the two thread-carriers proper. The thread-carrier J is the one normally in action, and the thread-carrier J' is the one to be used to introduce the special thread at the heel or 15 toe apex. These thread-carriers are movable in frame J². The thread-carrier J is fixedly attached to the lever J³, pivoted at J⁴ and having a roller J⁵ at the opposite end from the thread-carrier. The thread-carrier J' is 20 pivotally attached to the lever J⁶, which lever J⁶ is pivoted to the frame at J⁷. Beyond this pivot-point is connected one arm of the bell-crank J⁸, the other end of the bell-crank carrying the roller J⁹. As may be seen, if a 25 horizontal movement in the same direction be given to the rollers J⁵ and J⁹ the thread-carriers J and J' will be oppositely moved to move one into, the other out of, operative position. These rollers J⁵ and J⁹ are at different 30 levels and, in the operation of the machine, when the plunger I is in the low cam-surface H² are influenced by two cam-surfaces of the cam I³. When the plunger I is elevated, (which, as will hereinafter be described, is 35 accomplished automatically at the desired point in the formation of the heel or toe,) the cams I² and I³ are elevated and the upper surface of cam I² influences the roller J⁵ and the lower surface of said cam influences the 40 roller J⁹. The arrangement of the cam-surfaces I² and I³ are such that when the cams are elevated and rollers J⁵ and J⁹ moving in the direction of arrow, Fig. 1, in passing between these cams for a portion of the passage no effect will be produced upon the roller J⁵ or its corresponding thread-carrier J due to the cut-away portion i²; but the high portions of cam I² will act upon the roller J⁹ and its corresponding thread-carrier J' to 45 move it downward into operative position. Thus for a time both thread-carriers will be in operation. The further movement will maintain the thread-carrier J' in operative position, and the end of the cut-away portion i² having 50 been reached the upper surface of the cam I² will withdraw the thread-carrier J from operation. When the cams I² and I³ are brought to their low position and the rollers J⁵ and J⁹ moving in the reverse direction, the reverse 55 operation takes place—that is, the roller J⁵ travels over the upper portion of cam I³, and the thread-carrier J is brought into operation. The thread-carrier J' by means of the cut-away portion i³ of the lower portion of cam I³ 60 is maintained in operation until it passes beyond the cut-away portion i³, when the thread-

carrier J' is by the lower portion of cam I³ withdrawn from action.

From the foregoing it will be apparent that the thread-carriers J and J' can be thrown into and out of action only during reciprocation—that is, while machine is making the heel or toe—as the shift of the cam I² and I³ are dependent upon the movement of the cam-plate H, which in turn is dependent upon the movement of the arm G, which is operated only during reciprocation. The cams I² and I³ are each, in effect, two cams, each cam I² and I³ having portions acting on rollers J⁵ and J⁹; but the cut-away portions i² i³ cause 80 the cams to operate upon one roller, the one controlling the carrier to be thrown into action in advance of the operation upon the roller controlling the carriers to be thrown out of action.

I provide the following mechanism for shifting the plate h' at the proper time during reciprocation to cut in and out at the proper time the special thread-carrier J'. Upon the plate h' is the pin k.

K is a lever having a slotted end embracing the pin k. The lever K is pivoted to a projection k' on the frame of the machine. At the end of the lever opposite to the pin k is connected the plunger L. The plunger L 95 extends vertically through the frame of the machine and has on its upper surface the projecting head L'. Secured to the rack-plate E so as to be adjustable thereon is the plate M, having at its outer end the inclined cam-plate m. The cam-plate m is pivoted to the plate M, so as to be capable of moving inward, and is held normally in its outward position by means of a spring m'. The lowest point of the inclined cam-plate is such as to pass under the projecting head L' when the plunger L is at its lowest point, and the highest point of the cam-plates m M are such as to raise the plunger L a distance sufficient to lower the plate h' to bring the projection 105 h² under the influence of the lever G. Thus when the plunger L is in its elevated position, supported upon the top of the plates m and M, the special thread-carrier J' is thrown into action, and when the plunger is free from the plates m M the special thread-carrier J' is thrown out of action. The plunger L is 110 acted upon by the inclined cam-plate m during the movement of the rack-plate in forming the first part of the heel or toe, and by adjusting the plate M with reference to the rack-plate E the special thread-carrier J' may be introduced at the desired point in the formation of the heel or toe. When the rack-plate E has operated to throw out the desired 115 number of needles in the formation of the heel or toe, the pawl e is automatically reversed by mechanism fully described and illustrated in my previously-mentioned patent, so that the rack-plate will move in the opposite direction to widen out to form the remainder of the heel or toe, and when in this operation 120

the cam-plate *m* has passed beyond the head *L'* of the plunger, the plunger will by the action of the spring *l* descend, throwing the appropriate mechanism into operation to cut out the special thread-carrier *J'*.

As is well known in this class of machines, in forming the heel or toe first a needle on each side of those in action at each reciprocation is thrown out of action. After the knitting-cams have acted and after the desired number have been thrown out of action—that is, the goods have been sufficiently narrowed—the needles are again one by one thrown into action before the knitting-cam acts. As a consequence and in order to make the use of the special thread symmetrical on both sides of the apex it is necessary that the plunger *L* should be released at a point in the movement of the rack-plate *E* in advance of that which in the reverse movement of the cam-plate the plunger was operated upon by the cam-plate. It is for this reason that the cam-plate *m* is pivoted to the plate *M*, as described. In the path of movement of the plate *m* is a pawl *O*, inoperative in one direction of movement of the plate—the forward movement—and operative in the other direction of movement of the plate—to wit, the return movement. By this construction when in the return movement of the rack-plate the plate *m* strikes the pawl *O* it (the plate) is moved out of line of movement of the head *L'* of the plunger *L*, and the plunger *L* descends. This enables the descent of the plunger *L* and the consequent removal of the special thread-carrier to take place in advance of the point where it was elevated by the action of the plate *m*. By varying the extent of the projection of the plates *M m* beyond the rack-plate *E* the point at which in the formation of the heel and toe the special thread will be thrown in and out may be varied. As may be seen by this construction, when the machine is forming the heel and toe at any desired point therein a special thread-carrier is automatically thrown into action. Both the special and regular thread-carriers are in action for a few needles. Then the regular thread-carrier is thrown out of action. Then at the corresponding point in the widening the regular thread-carrier is again thrown into action, and finally the special thread-carrier is thrown out of action. As may be seen by reference to Figs. 7, 8, and 9, the regular thread-carrier *J* and the special thread-carrier *J'* are side by side in the frame *J²*. The position of the thread-carrier *J* is such that it occupies when down a position in direct alinement with the needles and at the center of the knitting-cams. I have devised mechanism whereby when the special thread-carrier is in operative position and the regular thread-carrier out of operative position the special thread-carrier or the operative end thereof will assume the position as shown in Fig. 9—that is, a position in direct alinement with the needles and at the dead-

center of the knitting-cams. The lever *J⁶* of the thread-carrier *J* is made in two parts. Each of these parts has at its end an orifice. 70 In one of the orifices—that in the inner part of the lever *J⁶*—is placed a pin *j³*, which has a threaded end. This threaded end coacts with a thread on the interior of the other of said orifices. The spring *j³* tends to turn the 75 outer part of the lever on this screw, and thus move the end of the carrier *J'* through which the thread passes laterally, as shown in Fig. 9. When the two thread-carriers are in action, Fig. 8, the thread-carriers *J J'* occupy the position there shown. When the thread-carrier *J* is elevated, the spring *j³* will cause the lower end of the carrier *J'* to move inward and assume the position shown in Fig. 9. When the thread-carrier *J* moves 85 down, it will overcome the action of the spring *j³*, forcing the lower end of the lever *J'* into the position shown in Fig. 8.

Having now fully described my invention, what I claim, and desire to protect by Letters 90 Patent, is—

1. In a circular-knitting machine, in combination a main thread-carrier normally in action and a supplemental thread-carrier normally out of action and needle-controlling mechanism to render certain needles inoperative and operative in a regular sequence to form the heel and toe of a stocking, intermediate devices operated by said needle-controlling mechanism after said operation commences to bring the supplemental thread-carrier into action and move the main thread-carrier out of action and prior to the termination of said operation to return the main thread-carrier into action and the supplemental thread-carrier out of action. 95

2. In a circular-knitting machine, in combination a main thread-carrier normally in action and a supplemental thread-carrier normally out of action and needle-controlling 110 mechanism to render certain needles inoperative and operative in a regular sequence to form the heel and toe of a stocking, intermediate devices operated by said needle-controlling mechanism after said operation commences to bring the supplemental thread-carrier into action, and subsequently to move the main thread-carrier out of action and prior to the termination of the movement of said needle-controlling mechanism to return the 115 main thread-carrier into action and subsequently remove the supplemental thread-carrier out of action. 120

3. In a circular-knitting machine, in combination a rack-plate adapted in its movement in one direction to move certain needles out of action in a regular sequence and in the movement in the other direction to return said needles into action, a main thread-carrier normally in action and a supplemental 125 thread-carrier normally out of action, intermediate devices operated by the rack-plate intermediate of its operation in one direction of its movement to move the supplemental 130

thread-carrier into operative position and the main thread-carrier out of operative position and intermediate of its operation in the other direction of its movement to return the main thread-carrier out of operative position.

4. In a circular-knitting machine, in combination a rack-plate adapted intermediate of its movement in one direction to move certain needles out of action in a regular sequence and in the movement in the other direction to return said needles into action, a main thread-carrier normally in action and a supplemental thread-carrier normally out of action, intermediate devices operated by the 15 rack-plate intermediate of its movement in one direction to move the supplemental thread-carrier into operative position and subsequently to move the main thread-carrier out of operative position and intermediate 20 of its movement in the other direction to return the main thread-carrier into action and move the supplemental thread-carrier out of action.

5. In a circular-knitting machine, in combination a main thread-carrier normally in action and a supplemental thread-carrier normally out of action, a cam-cylinder mechanism to reciprocate the cam-cylinder and mechanism operated during the reciprocation of 30 said cam-cylinder to bring the said supplemental thread-carrier into action after one or more courses have been knit and move the main thread-carrier out of action.

6. In a circular-knitting machine, in combination a main thread-carrier normally in action and a supplemental thread-carrier normally out of action, a cam-cylinder mechanism to reciprocate the cam-cylinder and mechanism operated during the reciprocation of 40 said cam-cylinder to bring the supplemental thread-carrier into action after one or more courses have been knit and move the main thread-carrier out of action, and subsequently to return the main thread-carrier into action 45 and move the supplemental thread-carrier out of action.

7. In a circular-knitting machine, in combination with a main thread-carrier normally in action and a supplemental thread-carrier normally out of action, a cam-cylinder mechanism to reciprocate the cam-cylinder and mechanism operated during the reciprocation of 50 said cam-cylinder to bring the supplemental thread-carrier into action after one or more courses have been knit, and subsequently to move the main thread-carrier out of action.

8. In a circular-knitting machine, in combination with a main thread-carrier normally in action and a supplemental thread-carrier normally out of action, a cam-cylinder mechanism to reciprocate the cam-cylinder and mechanism operated during the reciprocation of 60 said cam-cylinder to bring the supplemental thread-carrier into action after one or more courses have been knit, and subsequently to move the main thread-carrier out

of action, and subsequently to move said main thread-carrier again into action and subsequently to move supplemental thread-carrier 70 out of action.

9. In a circular-knitting machine, in combination with a main thread-carrier normally in action and a supplemental thread-carrier normally out of action, of a cam adapted to 75 throw the supplemental thread-carrier into action, a cam for throwing the main thread-carrier out of action, a cam-cylinder, means to reciprocate the cam-cylinder of said machine and mechanism operated during said 80 reciprocation after one or more courses have been knit to move said cams in line of movement of the thread-carriers.

10. In a circular-knitting machine, in combination with a main thread-carrier normally in action and a supplemental carrier normally out of action, of a cam adapted to throw the supplemental thread-carrier into action, a cam for throwing the main thread-carrier out of action, a cam-cylinder, means to reciprocate the cam-cylinder of said machine and means to move said cams in line of movement of the thread-carriers during said reciprocation after one or more courses have been knit, the supplemental-thread-carrier cam being in advance of the main-thread-carrier cam, whereby the supplemental thread-carrier is thrown into action before the main thread-carrier is moved out of action.

11. In a circular-knitting machine, in combination with a main thread-carrier normally in action and a supplemental thread-carrier normally out of action, of a cam adapted to throw the supplemental thread-carrier into action, a cam for throwing the main thread-carrier out of action, a cam-cylinder, means to reciprocate the cam-cylinder of said machine, a cam for returning the main thread-carrier into action and the supplemental thread-carrier out of action and means during said reciprocation after one or more courses have been knit to first move the first set of cams into line of movement of the thread-carriers and subsequently return said first set of cams and move said second set of cams into line of movement of said thread-carrier.

12. In a circular-knitting machine, in combination with a main thread-carrier normally in action and a supplemental thread-carrier normally out of action, of a cam adapted to throw the supplemental thread-carrier into action, a cam for throwing the main thread-carrier out of action, a cam-cylinder, means to reciprocate the cam-cylinder of said machine, cams for returning the main thread-carrier into action and the supplemental thread-carrier out of action and means during said reciprocation after one or more courses have been knit to first move the first set of cams into line of movement of the thread-carriers and subsequently return said first set of cams and move said second set of cams into line of movement of said thread-

carriers, the supplemental-thread-carrier cam being in advance of the main-thread-carrier cam in the first set of cams and vice versa in the second set of cams.

5 13. In a circular-knitting machine, in combination with a main thread-carrier normally in action, a supplemental thread-carrier normally out of action, of a pair of cams, one of said cams being operative to move the main thread-carrier into action and the supplemental thread-carrier out of action, a second pair of cams one of said last-mentioned set of cams being adapted to move the main thread-carrier out of action and the supplemental thread-carrier into action, said second pair of cams being in a different position from the first-mentioned set of cams, the first-mentioned set of cams being normally in line of movement of the thread-carriers, a cam-cylinder and means to reciprocate the cam-cylinder after one or more courses have been knit to move the first-mentioned set of cams out of line of movement of the thread-carriers and the second-mentioned set of cams into line of movement of the thread-carriers.

10 14. In a circular-knitting machine, in combination with a main thread-carrier normally in action, a supplemental thread-carrier normally out of action, of a pair of cams, one of said cams being operative to move the main thread-carrier into action and the supplemental thread-carrier out of action, a second pair of cams, one of said last-mentioned set of cams being adapted to move the main thread-carrier out of action and the supplemental thread-carrier into action, said second pair of cams being in a different position from the first-mentioned set of cams, the first-mentioned set of cams being normally in line of movement of the thread-carriers, a cam-cylinder and means to reciprocate the cam-cylinder after one or more courses have been knit to move the first-mentioned set of cams out of line of movement of the thread-carriers and the second-mentioned set of cams into line of movement of the thread-carriers, and subsequently to reverse the position of said sets of cams.

15 15. In a circular-knitting machine, in combination with a main thread-carrier normally in action, a supplemental thread-carrier normally out of action, of a pair of cams, one of said cams being operative to move the main thread-carrier into action and the supplemental thread-carrier out of action, a second pair of cams one of said last-mentioned set of cams being adapted to move the main thread-carrier out of action and the supplemental thread-carrier into action, said second pair of cams being in a different position from the first-mentioned set of cams, the first-mentioned set of cams being normally in line of movement of the thread-carriers, the main-thread-carrier cam of the first set of cams be-

ing in advance of the supplemental-thread-carrier cam and vice versa in the second set of cams, a cam-cylinder, means to reciprocate said cam-cylinder, and means during the reciprocation of the cam-cylinder after one or more courses have been knit to move the first-mentioned set of cams out of line of movement of the thread-carriers and the second-mentioned set of cams in line of movement of the thread-carriers.

20 16. In a circular-knitting machine, in combination with a main thread-carrier normally in action, a supplemental thread-carrier normally out of action, of a pair of cams, one of said cams being operative to move the main thread-carrier into action and the supplemental thread-carrier out of action, a second pair of cams one of said last-mentioned set of cams being adapted to move the main thread-carrier out of action and the supplemental thread-carrier into action said second pair of cams being in a different position from the first-mentioned set of cams, the first-mentioned set of cams being normally in line of movement of the thread-carriers, the main-thread-carrier cam of the first set of cams being in advance of the supplemental-thread-carrier cam and vice versa in the second set of cams, a cam-cylinder, means to reciprocate said cam-cylinder, and means during the reciprocation of the cam-cylinder after one or more courses have been knit to move the first-mentioned set of cams out of line of movement of the thread-carriers and the second-mentioned set of cams into line of movement of the thread-carriers, and subsequently to reverse the position of said sets of cams.

25 17. In a circular-knitting machine, in combination with a main thread-carrier normally in action, a supplemental thread-carrier normally out of action, of a pair of cams, one of said cams being operative to move the main thread-carrier into action and the supplemental thread-carrier out of action, a second pair of cams one of said last-mentioned set of cams being adapted to move the main thread-carrier out of action and the supplemental thread-carrier into action said second pair of cams being in a different position from the first-mentioned set of cams, the first-mentioned set of cams being normally in line of movement of the thread-carriers, needle-controlling mechanism to render certain needles inoperative and operative in a regular sequence to form the heel and toe of a stocking, intermediate devices operated by said needle-controlling mechanism, to move the first-mentioned set of cams out of line of movement with the thread-carriers and the second-mentioned set of cams in line of movement with the thread-carriers.

30 18. In a circular-knitting machine, in combination with a main thread-carrier normally in action, a supplemental thread-carrier normally out of action, of a pair of cams, one of said cams being operative to move the main thread-carrier into action and the supplemen-

tal thread-carrier out of action, a second pair of cams one of said last-mentioned set of cams being adapted to move the main thread-carrier out of action and the supplemental 5 thread-carrier into action said second pair of cams being in a different position from the first-mentioned set of cams, the first-mentioned set of cams being normally in line of movement of the thread-carriers, needle-controlling 10 mechanism to render certain needles inoperative and operative in a regular sequence to form the heel and toe of a stocking, intermediate devices operated by said needle-controlling mechanism, to move the 15 first-mentioned set of cams out of line of movement with the thread-carriers and the second-mentioned set of cams into line of movement with the thread-carriers, and subsequently to reverse the position of said sets 20 of cams.

19. In a circular-knitting machine, in combination with a main thread-carrier normally in action, a supplemental thread-carrier normally out of action, of a pair of cams, one of 25 said cams being operative to move the main thread-carrier into action and the supplemental thread-carrier out of action, a second pair of cams one of said last-mentioned set of cams being adapted to move the main thread-carrier 30 out of action and the supplemental thread-carrier into action, said second pair of cams being in a different position from the first-mentioned set of cams, the first-mentioned set of cams being normally in line of 35 movement of the thread-carriers, the main-thread-carrier cam of the first set of cams being in advance of the supplemental-thread-carrier cam and vice versa in the second set of cams, needle-controlling mechanism to render 40 certain needles inoperative and operative in a regular sequence to form the heel and toe of a stocking, intermediate devices operated by said needle-controlling mechanism, to move the first-mentioned set of cams out 45 of line of movement with the thread-carriers and the second-mentioned set of cams into line of movement with the thread-carriers.

20. In a circular-knitting machine, in combination with a main thread-carrier normally 50 in action, a supplemental thread-carrier normally out of action, of a pair of cams, one of said cams being operative to move the main thread-carrier into action and the supplemental thread-carrier out of action, a second pair of 55 cams one of said last-mentioned set of cams being adapted to move the main thread-carrier out of action, and the supplemental thread-carrier into action said second pair of cams being in a different position from the 60 first-mentioned set of cams, the first-mentioned set of cams being normally in line of movement of the thread-carriers, the main-thread-carrier cam of the first set of cams being in advance of the supplemental-thread-carrier 65 cam and vice versa in the second set of cams, needle-controlling mechanisms to render certain needles inoperative and oper-

ative in a regular sequence to form the heel and toe of a stocking, intermediate devices operated by said needle-controlling mechanism, to move the first-mentioned set of cams out of line of movement with the thread-carriers and the second-mentioned set of cams in line of movement with the thread-carriers, and subsequently to reverse the position of 70 said sets of cams.

21. In a circular-knitting machine, in combination with a main thread-carrier normally in action, a supplemental thread-carrier normally out of action, of a pair of cams, one of 80 said cams being operative to move the main thread-carrier into action and the supplemental thread-carrier out of action, a second pair of cams one of said last-mentioned set of cams being adapted to move the main thread-carrier 85 out of action and the supplemental thread-carrier into action, said second pair of cams being in a different position from the first-mentioned set of cams, the first-mentioned set of cams being normally in line of 90 movement of the thread-carriers, a rack-plate adapted in its movement in one direction to move certain needles out of action in a regular sequence and in the movement in the other direction to return said needles into action, of intermediate devices operated in one direction of movement by the rack-plate to move the first-mentioned set of cams out of line of movement of the thread-carriers and the second-mentioned set of cams into line of 95 movement of said thread-carriers and in the other direction of movement to reverse the positions of said sets of cams.

22. In a circular-knitting machine, in combination with a main thread-carrier normally 105 in action, a supplemental thread-carrier normally out of action, of a pair of cams, one of said cams being operative to move the main thread-carrier into action and the supplemental thread-carrier out of action, a second pair of 110 cams one of said last-mentioned set of cams being adapted to move the main thread-carrier out of action and the supplemental thread-carrier into action, said second pair of cams being in a different position from the 115 first-mentioned set of cams, the first-mentioned set of cams being normally in line of movement of the thread-carriers, a rack-plate adapted in its movement in one direction to move certain needles out of action in a regular sequence and in the movement in the other direction to return said needles into action, of intermediate devices operated in one direction of movement by the rack-plate to move the first-mentioned set of cams out of 120 line of movement of the thread-carriers and the second-mentioned set of cams in line of movement of said thread-carriers and in the other direction of movement to reverse the 125 positions of said sets of cams, the main-thread-carrier cam of the first set of cams being in advance of the supplemental-thread-carrier cam and vice versa in the second set of cams.

23. In a circular-knitting machine in combination with a main thread-carrier normally in action, a supplemental thread-carrier normally out of action, of a pair of cams, one of said cams being operative to move the main thread-carrier into action and the supplemental thread-carrier out of action, a second pair of cams one of said last-mentioned set of cams being adapted to move the main thread-carrier out of action and the supplemental thread-carrier into action, said second pair of cams being in a different position from the first-mentioned set of cams, the first-mentioned set of cams being normally in line of movement of the thread-carriers, a plunger carrying said cams, a pivoted cam-plate having cam-surfaces at different levels, said plunger dependent upon the position of the cam-plate resting upon one or the other of said surfaces, a vertically-movable slide having projections from opposite sides at different levels, a cam-cylinder mechanism to reciprocate the cam-cylinder, a lever and connection between said cam-cylinder mechanism and the lever, said movable slide being in line of movement of said lever, and mechanism adapted during the reciprocation of said cam-cylinder to move said slide in one direction.

24. In a circular-knitting machine in combination with a main thread-carrier normally in action, a supplemental thread-carrier normally out of action, of a pair of cams, one of said cams being operative to move the main thread-carrier into action and the supplemental thread-carrier out of action, a second pair of cams one of said last-mentioned set of cams being adapted to move the main thread-carrier out of action and the supplemental thread-carrier into action, said second pair of cams being in a different position from the first-mentioned set of cams, the first-mentioned set of cams being normally in line of movement of the thread-carriers, a plunger carrying said cams, a pivoted cam-plate having cam-surfaces at different levels, said plunger dependent upon the position of the cam-plate resting upon one or the other of said surfaces, a vertically-movable slide having projections from opposite sides at different levels, a cam-cylinder mechanism to reciprocate the cam-cylinder, a lever and connection between said cam-cylinder mechanism and the lever, said movable slide being in line of movement of said lever, and mechanism adapted during the reciprocation of said cam-cylinder to move said slide in one direction, and subsequently return said slide to its initial position.

25. In a circular-knitting machine in combination with a main thread-carrier normally in action, a supplemental thread-carrier normally out of action, of a pair of cams, one of said cams being operative to move the main thread-carrier into action and the supplemental thread-carrier out of action, a second pair of cams, one of said last-mentioned set of cams being adapted to move the main thread-

carrier out of action and the supplemental thread-carrier into action, said second pair of cams being in a different position from the first-mentioned set of cams, the first-mentioned set of cams being normally in line of movement of the thread-carriers, a plunger carrying said cams, a pivoted cam-plate having cam-surfaces at different levels, said plunger dependent upon the position of the cam-plate resting upon one or the other of said surfaces, a vertically-movable slide having projections from opposite sides at different levels, a cam-cylinder mechanism to reciprocate the cam-cylinder, a lever and connection between said cam-cylinder mechanism and the lever, said movable slide being in line of movement of said lever, needle-controlling mechanism to render certain needles inoperative and operative in a regular sequence during said reciprocation, intermediate devices operated by said needle-controlling mechanism to move said slide in one direction.

26. In a circular-knitting machine in combination with a main thread-carrier normally in action, a supplemental thread-carrier normally out of action, of a pair of cams, one of said cams being operative to move the main thread-carrier into action and the supplemental thread-carrier out of action, a second pair of cams, one of said last-mentioned set of cams being adapted to move the main thread-carrier out of action and the supplemental thread-carrier into action, said second pair of cams being in a different position from the first-mentioned set of cams, the first-mentioned set of cams being normally in line of movement of the thread-carriers, a plunger carrying said cams, a pivoted cam-plate having cam-surfaces at different levels, said plunger dependent upon the position of the cam-plate resting upon one or the other of said surfaces, a vertically-movable slide having projections from opposite sides at different levels, a cam-cylinder mechanism to reciprocate the cam-cylinder, a lever and connection between said cam-cylinder mechanism and the lever, said movable slide being in line of movement of said lever, needle-controlling mechanism to render certain needles inoperative and operative in a regular sequence during said reciprocation, intermediate devices operated by said needle-controlling mechanism to move said slide in one direction and subsequently return said slide to its initial position.

27. In a circular-knitting machine in combination with a main thread-carrier normally in action, a supplemental thread-carrier normally out of action, of a pair of cams, one of said cams being operative to move the main thread-carrier into action and the supplemental thread-carrier out of action, a second pair of cams one of said last-mentioned set of cams being adapted to move the main thread-carrier out of action and the supplemental

thread-carrier into action, said second pair of cams being in a different position from the first-mentioned set of cams, the first-mentioned set of cams being normally in line of movement of the thread-carriers, a plunger carrying said cams, a pivoted cam-plate having cam-surfaces at different levels, said plunger dependent upon the position of the cam-plate resting upon one or the other of said surfaces, a vertically-movable slide having projections from opposite sides at different levels, a cam-cylinder mechanism to reciprocate the cam-cylinder, a lever and connection between said cam-cylinder mechanism and the lever, said movable slide being in line of movement of said lever, a rack-plate adapted in its movement in one direction to move certain needles out of action in a regular sequence and in the movement in the other direction to return said needles into action, intermediate devices operated by the rack-plate in one direction of its movement to move said slide in one direction and in the other direction of its movement to return the slide to its initial position.

28. In a circular-knitting machine in combination with a main thread-carrier normally in action, a supplemental thread-carrier normally out of action, of a pair of cams, one of said cams being operative to move the main thread-carrier into action and the supplemental thread-carrier out of action, a second pair of cams, one of said last-mentioned set of cams being adapted to move the main thread-carrier out of action and the supplemental thread-carrier into action, said second pair of cams being in a different position from the first-mentioned set of cams, the first-mentioned set of cams being normally in line of movement of the thread-carrier, a plunger carrying said cams, a pivoted cam-plate having cam-surfaces at different levels, said plunger dependent upon the position of the cam-plate resting upon one or the other of said surfaces, a vertically-movable slide having projections from opposite sides at different levels, a cam-cylinder mechanism to reciprocate the cam-cylinder, a lever and connection between said cam-cylinder mechanism and the lever, said movable slide being in line of movement of said lever, a rack-plate adapted in its movement in one direction to move certain needles out of action in a regular sequence and in the movement in the other direction to return said needles into action, intermediate devices operated by the rack-plate in one direction of its movement to move said slide in one direction and in the other direction of its movement to return the slide to its initial position.

30. In combination, a thread-carrier frame, two thread-carriers supported in said frame side by side, one of said thread-carriers having a pivoted operative portion adapted to move toward the other carrier and a spring tending to move said pivoted portion in that direction.

31. In combination, a thread-carrier frame, two thread-carriers supported in said frame side by side, one of said thread-carriers having a portion adapted to move toward the other carrier and a spring tending to move said movable portion in that direction.

32. In combination, a thread-carrier frame, two thread-carriers supported in said frame side by side, one of said thread-carriers having a portion adapted to move toward the other carrier and a spring tending to move said movable portion in that direction.

33. In combination, two thread-carriers and means to move said carriers in and out of operative position, one of said carriers having a portion adapted when said carrier is in operative position to move into the operative position of the other carrier when the last-mentioned carrier is out of operative position.

34. In combination, two thread-carriers and means to move said carriers in and out of operative position, one of said carriers being adapted when said carrier is in operative position to move into the operative position of the other carrier when the last-mentioned carrier is out of operative position.

35. In combination, two thread-carriers, means to move said carriers in and out of operative position, and means to retain both

said thread-carriers simultaneously in operation, one of said carriers being adapted when said carrier is in operative position to move into the operative position of the other carrier when the last-mentioned carrier is out of operative position.

In testimony of which invention I have

hereunto set my hand, at Philadelphia, on this 9th day of April, 1901.

HARRY A. HOUSEMAN.
